GARMENT PRESSING MACHINE

Herbert G. Beede, Pawtucket, R. I.

Application May 21, 1931, Serial No. 539,089

8 Claims. (Cl. 68—9)

My invention relates to garment pressing machines for use in tailoring, dry cleaning, laundering, clothing manufacturing and other establishments for steaming, shaping and pressing garments, and the invention relates more particularly to means for actuating and controlling movements of the movable pressing element or member.

The principal object of the invention is to provide in a machine of the above type, means for producing heavier pressure than is available in machines now in use for the same purpose by comparatively slight effort and with a very limited motion of the actuating foot pedal. In connection with the accomplishment of this object I provide 10 a connection between the foot pedal lever and the primary link of the first toggle to afford an easy start in closing the press by an arrangement under which the action or relative movements of the pedal lever and connection is the reverse of 15 a closing toggle action when the foot pedal is moved to close the press, and under which arrangement the final motion or direction of pull when the head is practically closed will be at approximately right angles to the foot pedal lever.

Another object of the invention is to provide a 20 machine of the above character and provided with a system of triple toggle leverages in which all of the secondary links of the toggles act at approximately right angles to the direction of motion.

Another object of the invention is to provide a self-aligning thrust bearing for the primary link of the first toggle to prevent binding where a plurality of swinging joints are to be aligned.

Another object of the invention is to provide 25 suitable counterbalanced toggle members to return the upper pressing element to open position when the toggles are broken.

Another object of the invention is to provide 30 in connection with toggle operated pressing machines a rebound check which acts to retard the upward motion of the head so that immediately upon opening the press under heavy pressure the rebound check will become operative to absorb 35 the sudden release of rebound force when unlatching the press or breaking the toggle and then to gradually check further opening motion of the head in accordance with the action of the levers and counterbalancing weights.

Another object of the invention is to provide 40 a rebound check of the above character which is inoperative during closing of the press when the head moves downward to the buck.

Other objects of the invention include the provision of a check of the above character and for

the above purposes which may be readily removed from the press for repair or replacement; and the provision of a check in which the wear may be readily taken up and which is easily adjustable for controlling the checking action; and in which the friction or breaking means are self-centering.

Other objects and advantages of the invention will be brought out and become apparent during the course of the following detail description of 10 the accompanying drawings wherein is illustrated a preferred embodiment of the invention and in which,

Fig. 1 is a side elevation partly in section of a garment pressing machine with the invention 15 applied thereto, the machine being shown in closed position;

Fig. 2 is a view similar to Fig. 1 showing the machine in open position;

Fig. 3 is a central horizontal sectional view 20 through the friction check;

Fig. 4 is a side elevation of the friction check with a portion of the housing broken away and showing the connection with the toggle; and

Fig. 5 is a diagrammatic view illustrating the 25 checking action.

Referring to the drawings, the numeral 10 designates the main supporting frame of the machine having an upright extension 11. The lower pressing element or buck 12 is mounted at the 30 front of the frame 10, and a table 13 is mounted on the frame convenient to the buck. The upper pressing element or head 14 is carried on the swinging arm 15 which is pivoted on the extension 11 at 16 and to the rear end of which is secured a counterweight 17. A toggle member 18 is operatively connected to the arm 15 and is pivotally connected at 19 to the upper end of the main toggle lever 20 which is pivoted on the frame 10 at 21. The head 14 is operated to move 40 toward the buck 12 under very great pressure and with comparatively slight effort through the arrangement of toggle links connected between the main toggle lever 20 and the foot lever 22 which is pivoted at one end to the frame at 23, a pedal 45 24 being provided at its outer end.

The system of toggles through which the great pressure is obtained comprises a link 25 connected to the pedal lever 22 at 26 and to the primary link 27 at 28 in such a manner that 50 when the press is closed as shown in Fig. 1, the link 25 is disposed at substantially right angles to the pedal lever 22 with the pivots 26 and 28 aligned in a plane substantially at right angles to the pedal lever 22 and when the press is open, 55

the pivots 26 and 28 are alined in a plane intersecting the lever 22 approximately at an angle of 45 degrees. It will be apparent that the relative positions and movements of the pedal lever 22 and link 25 are such that their action during closing of the press affords an easy start to movement of the parts about to be described.

The primary link 27 is pivoted at 30 to the self-aligning thrust bearing 29, which will be hereinafter described in details of construction and purpose, and to one end of the secondary link 31 of the first toggle at 32. It will be noted that in the open position of the press, the pivot 32 is in the same plane with the pivots 26 and 28 to the left of pivot 28, but that in closed position it is at the right of pivots 26 and 28 having swung through an arc thereacross during closing of the press. The secondary link 31 of the first toggle is provided with a counterweight 33 at its other end and is pivoted at 34 to the primary link 35 of the second toggle, which is pivoted at 36 to the frame 10 and which is provided at one end with a counterweight 37. The secondary link 38 of the second toggle is pivotally connected to the primary link 35 at 39 and to the main lever 20 at 40.

The parts 15, 18, 20, 38 and 35 in both open and closed position of the machine are disposed in the same relative positions in which the corresponding parts are disposed in the patent to H. G. Beede, No. 1,661,153, but in that patent the link corresponding to the link 35 is connected to the pedal lever by a single link which only exerts a direct pull on the part corresponding to lever 35. Under the present arrangement, much greater pressure is obtained on the upper pressing element by the system of triple toggles arranged as described above and as will be obvious the operation is accomplished with much less effort on the foot pedal 24. The present invention can be applied to machines embodying structure similar to that disclosed in the above identified patent.

In order to lock the head closed for continued pressure on the garments disposed between the head and buck, the first toggle, parts 27 and 31, may be so adjusted as shown in the drawings whereby they assume a position in which the pivot 32 moves beyond a line between the pivots 30 and 34. This is the preferred manner of locking the press closed for continued pressure, and in order to break the toggle lock and open the press, I provide an independent trip pedal 41 adjacent the foot pedal 24. This trip pedal 41 is fulcrumed to the frame 10 at 42. An extension 43 on the foot lever 22 is disposed immediately above the inner end of the trip pedal 41 when the press is locked in closed position as shown in Fig. 1 and in order to break the toggle between links 27 and 31, the operator depresses the outer end of the trip pedal 41 with sufficient force to lift the inner end against the extension 43 to raise the foot lever 22 sufficient to carry the pivot 32 above the line between pivots 30 and 34 following which the counterweights 17, 37 and 33 will move the parts to which they are attached to carry the head 14 upwardly and return the links to the position shown in Fig. 2.

The thrust bearing 29 comprises a preferably round shaft flattened at one end around the pivot 30 where it is joined to the primary lever 27. The thrust bearing is mounted within the recess 60 and is rotatably secured therein by means of the bolt and nut 61. It will be obvious that the thrust bearing takes its thrust against

the end of the recess 60 and can partially rotate in recess 60. Thus the primary lever 27 being connected to the movable thrust bearing instead of to a fixed pivot on the frame, there will be no binding when the links are operated to close and open the toggles to move the head 14 to and from the buck 12 in the manner which will be obvious from the foregoing description.

In order to check the return of the head 14 to open position against sudden and jarring movement, I provide the friction check 50, which is shown in detail in Figs. 3, 4, and 5, and which comprises the housing 51 having a flange 52 engageable around the opening 53 in the front of the frame 10 and secured to the frame by bolts 54. The forked lever 55 is pivotally connected to the casing 51 at 56 and is operatively associated with friction check mechanism within the casing and hereinafter described in detail. The link 35 has an extension 57 provided with the roller or lug 58 which is embraced between the forks of the lever 55 so that as the extension 57 moves with the link 35 upwardly and as the press fulcrums, it turns the arm 55 on shaft 56 and operates the friction check mechanism within the casing 51. Shaft 56 is removably held in the casing by the cotter pin 56'.

As has been mentioned, the arm 57 of the link 35 is provided with a lug or roller 58 which is disposed between the arms 63 of the lever 55, 30 the lever having spaced arms 64 which are journaled on the shaft 56 through the housing 51 for oscillating movement as shown in dotted lines in Fig. 4. A pawl 65 is pivoted to the lever 55 at 66 and bears against a spring 67 which is mounted between the pawl and an extension 68 of the lever 55. The ratchet wheel 69 is journaled on the shaft 56 and is reduced on each face as at 70 to provide seats for the brake discs 71 outside of which are the friction plates 72, 40 each including a circular plate mounted on the shaft 56 and an integral offset extension 73 outside of the lever arms 64. Screws 73' hold the friction plates against rotation. One plate 72 has a rib 74 formed diametrically thereacross 45 abutting one surface of a forked lever 75 which is pivotally mounted on the housing at opposite points on rods 76, 77. The adjusting screw 78 has screw threaded engagement through an opening in a boss 79 on the housing and abuts a 50 spring 80 seated in a recess 81 in the lever 75.

When the press is in open position, the pawl 65 is in the full line position shown in Fig. 4 and as the press head is moved to closed position, the arm 57 swings downwardly to carry 55 the roller or lug 58 through the arc shown in dotted lines in Fig. 4, during which time the pawl 65 is moved downwardly with the lever 55 across the ratchet teeth so that none of the parts within the housing except the lever arms 64 move. However, when the press is opened the arm 57 swings up carrying the lug or roller 58 through the same arc thereby carrying the lever 55 up with the pawl 65 engaged against one of the ratchet teeth on the ratchet wheel 69 60 whereby the ratchet wheel is rotated against the friction discs 71.

It should be apparent from the foregoing description and the disclosure of the drawings that the friction discs, the arms 64 of the lever 70 55 and the friction plates and ratchet wheel are all carried on the shaft 56 and are free to move endwise of the shaft so that pressure applied by the lever 75 on the rib 54 at opposite points of the shaft 56 produces equal pressure on both 75

brake discs and on both sides of each brake disc. This pressure can be adjusted, that is, increased or diminished by adjustment of the screw 78 relative to the spring 80 so that if the machine 5 is delivered in properly adjusted condition and the arm 15 returns to open position at a properly regulated speed due to proper adjustment of the friction check and then due to wear on the brake discs, the arm 15 returns to open position too 10 fast, the screw 78 can be readily adjusted until the proper braking is had. It should also be obvious that the brake discs can be readily replaced, as the friction check housing is removable from the frame 10 simply by removing the 15 bolts 54 and withdrawing the shaft 56 to permit removal of the old brake discs and insertion of new ones. In fact any of the parts of the friction check can be readily replaced in the same manner.

20 As has been explained, when the foot pedal 24 is depressed, the lever 22 pulls on the link 25, which in turn pulls the primary lever 27 from the position of Fig. 2 to the position of Fig. 1, wherein the pivot 32 passes a line through the 25 center of pivots 30 and 34 and during which movement arm 15 is moved by the toggle members 18, 20, 35 and 31 to closed position. Of course, the weights 17, 37 and 33 have been raised and are held in raised position by the 30 locking action of the toggle links 27 and 31 due to the location of the pivot 32 beyond the line through pivots 30 and 34. When the press is to be opened, the trip pedal 41 is operated against the extension 43 to break the toggle lock and 35 permit the weights 17, 37 and 33 to return the toggles to the position of Fig. 2 while raising the head 14. The action of the friction check takes place to absorb the sudden release of rebound force almost immediately upon or simultane- 40 ously with the breaking of the toggle joints to permit the weights to return the head to open position because as soon as the toggle joints are broken, lever 35 begins to move under the action of weight 37 and the arm 57 swings up- 45 wardly with the pawl 65 engaged against one of the ratchet teeth on the ratchet wheel 69 and the ratchet wheel is constantly in adjusted frictional engagement with the brake discs 71.

In Fig. 5, I have illustrated by graphic chart 50 in connection with a diagrammatic view of the arm 57 and friction check parts, the theoretical and actual motions showing that if the opening motion of the press was produced by true rotating motion, the friction check would have a 55 friction increase as the press opens, whereas the opening of the press controlled by the toggle mechanism actually produces a decrease in friction as the press opens with a decided excess of friction at the start. This provides or affords 60 a decided advantage in checking the sudden release of pressure, as the momentum is impeded at the start of the opening of the press.

While I have shown the friction check in 65 connection with a triple toggle pressing machine system, I wish it to be understood that the same may be applied to other arrangements of toggle mechanism wherein upward motion is imparted to the head upon breaking toggle joints in accordance with the action of the levers and counterbalanced weights.

I claim:

1. In a garment pressing machine including a frame and a movable pressing element, a support for said element, actuating means for said 75 element comprising a toggle having one of its

links connected to the element support, a bell crank lever pivoted to the frame intermediate its ends and connected to said toggle adjacent one end, a friction check, a connection between said bell crank lever adjacent its other end and friction check, means for rotating said bell crank lever on its pivot, said friction check being operable by said bell crank and connection to retard opening movement of said bell crank and element support and inoperable during closing 10 movement of said bell crank and element support.

2. In a garment pressing machine including a frame, a pressing element movable thereon to open and closed position, a toggle for moving said element connected thereto, a bell crank lever for moving said toggle connected thereto, said bell crank lever having a counterbalancing weight at one end, an extension on the other end of said bell crank, a friction check, means connecting said friction check and extension on the bell crank, and means for rotating said bell crank lever and means connecting it to the friction check to operate said friction check, said friction check being operable to retard movement of said bell crank and pressing element only in the direction of opening movement under the action of said counterbalancing weight.

3. In a garment pressing machine including a frame and a movable pressing element supported thereon, a toggle for moving said element to closed position, a lever to actuate said toggle, a toggle for actuating said lever and including pivotally connected links one of which is pivoted to the frame and the other to said lever, a pedal lever, and a link pivoted to said first link independently of said other link and also pivotally connected to the pedal lever for movement thereby and relative thereto when the pedal lever is moved, the pivotal connection between the links of the second toggle being positioned relative to the pivotal connection between said last and first links for movement thereacross during opening and closing movements of the press.

4. The structure of claim 3 wherein the pivots connecting the links of the second toggle, first and last links, and last link and pedal lever respectively are substantially in alinement at open position of the press.

5. In a garment pressing machine including a frame and a movable pressing element, a lever supporting said element, a toggle operatively connected to said lever to move said element to open and closed positions, a second lever operatively connected to said toggle, a second toggle having one member pivotally connected to said second lever and its other member pivotally connected to a fixed support adjacent its lower end and standing in substantially vertical position when the element is in open position, the upper end of said other member being pivotally connected to said first member, a pedal lever, and a link pivotally connected thereto and to said other member, said last connection being at a point on said other member about which the connection between said members of the second toggle will swing when the pedal lever is depressed.

6. In a garment pressing machine including a frame and a movable pressing element, a lever supporting said element, a toggle operatively connected to said lever to move said element to open and closed positions, a second lever operatively connected to said toggle, a second toggle having one member pivotally connected to said second lever and its other member pivotally connected

to a fixed support adjacent its lower end and standing in substantially vertical position when the element is in open position, the upper end of said other member being pivotally connected to said first member, a pedal lever, and a link pivotally connected thereto and to said other member, said last connection being at a point on said other member substantially in alinement with the pivotal connection between the link and pedal lever and the connection between the members of said second toggle and about which the connection between said members of the second toggle will swing when the pedal lever is depressed.

7. In a garment pressing machine including a movable pressing element support, a main toggle operatively connected to said support, a pedal lever, a link connected at its lower end to said pedal lever, a second toggle having one of its members pivotally connected to the frame and also connected to the other end of said link and disposed at open position of the press in substantially upright position, the members of said second toggle being pivotally connected at a point movable across the points of connection of the

link to the specified member of the second toggle during closing movement of the press, and means whereby the straightening of said second toggle will straighten said first toggle and move said pressing element support to close the press.

8. In a garment pressing machine including a frame and having a movable pressing element support, a main toggle operatively connected thereto, a second toggle having one link pivotally connected to the frame and standing in upright position at open position of the press, the other link of said second toggle being pivotally connected to the first link adjacent its upper end, a pedal lever, a link pivotally connected to said first link of the second toggle and to said pedal lever and inclined upwardly and toward the front of the frame and at an acute angle to said pedal lever at open position of the press and being substantially at right angles to the pedal lever at closed position of the press, and means whereby straightening of said second toggle will straighten said first toggle and close the press.

HERBERT G. BEEDE.
